J. T. SIMPSON.
PROCESS OF MAKING REINFORCED CONCRETE STRUCTURES.
APPLICATION FILED JAN. 25, 1918.

1,428,401.

Patented Sept. 5, 1922.

UNITED STATES PATENT OFFICE.

JOHN T. SIMPSON, OF NEWARK, NEW JERSEY.

PROCESS OF MAKING REINFORCED CONCRETE STRUCTURES.

Application filed January 25, 1918. Serial No. 213,640.

To all whom it may concern:

Be it known that I, JOHN T. SIMPSON, a citizen of the United States, and a resident of Newark, in the county of Essex and State 5 of New Jersey, have invented a certain new and useful Process of Making Reinforced Concrete Structures, of which the following is a specification.

My invention relates to processes of building concrete structures wherein reinforced concrete shop cast elements are united by and to field cast reinforced concrete elements, and is directed more particularly to the construction of buoyant vessels such as boats, 15 barges, lighters and ships for marine transportation.

The objects of my invention are to improve the strength and durability of the structure, to expedite the construction, reduce the cost, improve the appearance and 20 reduce the expense of transportation of materials to the point where the structure is to be erected.

These and further objects will more fully appear in the following specification and accompanying drawings considered together or separately.

I have illustrated one embodiment of my invention in the accompanying drawings in 30 which like parts in all of the several figures are designated by similar characters of reference, and in which

Figure 1 is a deck plan view of a barge or lighter constructed according to my process.

Figure 2 is a fore and aft section or in-board profile of the same taken on the line 2—2 of Figure 1.

Figure 3 is a transverse section, on an enlarged scale, taken on the line 3—3 of Figure 1.

Figure 4 is a view similar to Figure 3 but showing the shop cast skin plates in position to receive the field cast elements.

Figure 5 is a detail section showing the mold in position to produce that portion shown in the dotted circle α of Figure 3.

Figure 6 is a detail section on the line indicated by 6—6 of Figure 2 showing the 50 keel mold in position.

Figure 7 is a detail section on the line indicated by 7—7 in Figure 3 showing the mold for a stanchion and for supporting the shop cast bulkheads.

Figure 8 is a detail section on the line

indicated by 8—8 in Figure 1 showing a mold for a deck beam and a mold for a hatch combing, and

Figure 9 is a diagrammatic section of a house erected by my process. 60

According to my process I produce a structure comprising shop cast elements or plates and field cast elements, the two being combined and permanently connected together to form a monolithic structure by the 65 operation of molding the field cast elements.

By "shop-cast" elements I mean those portions of the structure which are not molded during the construction of the vessel. These elements are manufactured in a 70 factory which may be at a great distance from the point of assembly. They may be machine cast in a well equipped shop. Each of the different shapes required will be the exact counterpart of the other shapes of its 75 size. The surfaces will be smooth. The parts may be artificially dried and seasoned thereby speeding up construction. The cost will be greatly reduced. One shop may turn out sufficient shapes to keep several assembling plants busy. The shop cast shapes are few in number and vessels of any size and tonnage may be constructed. The liability of producing defective work will be 80 reduced to a minimum and inspection will 85 be greatly facilitated.

By "field cast" elements I mean those parts of the vessel which are molded during the operation of assembling the shop cast elements at the waterside in order that the 90 finished structure may be launched. The elements are combined so that the field cast part will interlock with the reinforcements of the shop cast parts and form a unitary structure. The field cast and shop cast elements are further locked together to prevent 95 separation of the parts due to strains.

The shop cast elements form part of the mold of the other elements and the wetted portion of the hull of the vessel is composed 100 entirely of shop cast elements.

In the drawings 1 designates a decked barge or lighter which may be of any desired length, beam and depth of hold. The hull is composed of deck plates 2, sides plates 3 105 and bottom plates 4, all composed of shop cast reinforced concrete slabs. Each of the skin plates, except the midship rows extending lengthwise of the vessel from the deck line forward to the deck line aft and running 110

2

along the bottom, and the top row of plates, is provided with a flange 5 on one side thereof adjacent the edge thereof and surrounding the plate. Each of the flanged edges of 5 the plate is provided with a recess 6 extending the entire edge of the plate. The recess 6 therefore forms a groove extending entirely around the plates mentioned. When the plates are placed side by side and end to 10 end there will be a recess double the depth of each groove at the joining edges of the plates. The overall dimension of the flanged side of the plate being a trifle less than that of the other side of the plate, a slot 7 will be 15 formed at each joint and the slots will communicate with the recesses.

The top line 8 of plates have the flanges extending around three sides only, the fourth or top side being unflanged for a purpose to be hereinafter specified.

The two midship rows 9 of plates are provided with a flange 5 and a recess 6 on three sides only. The fourth side of each plate 9 is provided with an enlargement 10 25 on the side opposite the enlargement 6. The flange 10 is set back a short distance from the edge of the plate and a recess 11 extends through that side of the plate.

The plates 4, 8 and 9 are of the shape desired. In a barge, as illustrated, most of them are flat. Those joining the side and bottom plates may be angular or curved and the plates at the corners are curved to give the vessel a rounded form fore and aft. It 30 will be understood that the plates may be made of any shape in order that the vessel may have the conventional shapes of bows and stern.

The plates are reenforced by means of 40 two layers of galvanized wire netting of large mesh and the wires project beyond the edges of the plates and inward at right angles to the surface of the plate.

The shop cast elements above described 45 are preferably set up in a cradle 12 as shown in Figure 4. This cradle is constructed of longitudinal bottom stringers 13 located below the fore and aft joints between the plates, and lateral beams 14 beneath the 50 athwartship joints between the plates. Vertical beams 15 back up the vertical joints between the side plates and longitudinal beams 16 extend completely around the hull in line with the longitudinal seams between 55 the side plates 3. The beams 15 extend upwardly to approximately the ultimate height of the hull. A heavy sill 17 supports the central line 9 of plates by engagement with the flanges 10 of such plates and the sill extends upward at both ends to the ultimate 60 height of the hull. The stringers, beams and sill are properly braced from the outside and certain of the stringers may form the ways from which the vessel is to be 65 launched.

The stringers, beams and sill define the shape of the hull and the plates may be temporarily secured to them or the plates may be braced from the inside.

The recesses 6 and 11 and the slots leading to the recesses are now securely calked from the inside preferably with pitch and oakum. The entire skin, or what would be the planking of a wooden ship, is now in place and, to all outward appearances, the 70 75 hull is complete.

A mold such as 18 of proper width is now placed in position along each longitudinal seam of the bottom of the hull. These molds define the keel 19 and longitudinal 80 braces 20. Similar molds are placed at right angles and intersect the molds 19 and 20. These latter molds define the floor beams 22 of the vessel. Reinforcements, such as 23, are now placed within the molds and extend 85 longitudinally thereof. The reinforcements of the floor beams cross those in the longitudinal molds. The projecting reinforcements of the plates 4 and 9 extend into the molds.

90 Concrete is now poured into the molds until the level 7 is reached. Floor slabs 24 are now placed in position resting on the beams so far cast with their edges spaced apart and with reinforcements projecting 95 into the spaces. At certain of the joints the spaces between slabs are filled with concrete to the level of the upper surfaces of the slabs. Molds 25 are now placed above and in line with certain of the molds 18 and rest 100 upon the floor slabs. Longitudinal bulkhead slabs 26 and lateral bulkhead slabs 27 are now placed in vertical position with their bottom edges resting on certain of the molds 25 but not in contact with each other. 105 The reinforcements of the lower edges of the bulkhead slabs project into the molds 25 and those on the vertical edges thereof extend into the spaces between the vertical edges of the slabs.

110 A mold 28 is now placed over and in line with each mold 25. At the intersections of the longitudinal and lateral molds vertical molds 29 are erected. These molds embrace the vertical edges of the bulkheads where 115 they occur and concrete is poured into the molds 28 and 29 filling the molds 25 to the top of molds 28 and embedding the lower edges and projecting reinforcements of the bulkheads. The vertical molds 29 defining 120 stanchions 29^a and the vertical extensions of the longitudinal and lateral molds are filled with concrete to within a short distance below the lowermost horizontal side and bow and stern seams.

125 A horizontal mold 30 is now placed entirely around the inside of the hull and encloses the horizontal flanges 5 on either side of the said seam. These molds intersect the vertical members of the longitudinal and 130

lateral molds and may be supported and braced in any preferred manner. The open side of the mold 30 may be forced into intimate contact with the inside of the skin 5 plates by the following instrumentalities.

The reinforcements of the plates project into the mold. A wire 31 bent upon itself to form a staple is passed through perforations in the wall of the mold 30 opposite 10 the plates. The ends of this wire are made fast to the reinforcements projecting from the plates. Between the bend of the wire 31 and the outer surface of the mold a wedge 32 is driven. This will draw the open side 15 of the mold into close contact with the inside of the plates. A filling opening 33 may be left in the top side of the mold and concrete may be poured therein until the vertical molds and the mold 30 are filled to 20 the level of the top wall of the latter and forms a ribbon 33^a or shelf extending entirely around the hull.

The hull is built up in the above described manner until the required height is attained.

25 A mold is now placed around the entire upper edge of the hull and encloses the upper edges of the upper row of plates and their projecting reinforcements. This mold will define a heavy sill 34 which will encircle 30 the structure. Horizontal lateral molds in alinement with the ribs, and longitudinal molds in alinement with the bottom beams are now placed in position resting on 35 and communicating with the molds of the vertical extensions of the ribs and beams and the stanchions and define deck beams 35. Proper reinforcing members are placed in the sill and deck beam molds and the reinforcements of the plates, ribs, bulkheads and 40 stanchions project into such molds. Bolts 36 are placed within the sill mold and project through the outer wall thereof. The outer wall of the sill mold is somewhat higher than its inner wall and the walls of 45 the deck beam molds.

All of the molds are provided with wires such as 37 passing through alined perforations in opposite walls thereof. These wires are for the purpose of maintaining the reinforcing members in position before and during the field casting operation.

Concrete is now poured into the above described molds embedding the reinforcements therein and the projecting edges of the skin 55 plates and bulkheads and their projecting reinforcements.

Deck plates 2 are now laid in position resting on the deck beams and sill with spaces between their contiguous edges. The 60 reinforcements of the deck plates project into the spaces. The spaces between deck plates and the top of the sill mold to the level of the tops of such plates are filled with concrete flush with the tops of the plates. 65 Certain of the reinforcements of the deck

beams and those of the ribs and stanchions may also project into such spaces and thereby bind the parts with closer relation.

Certain of the deck plates 2 are provided with openings to form hatches 38. When 70 the deck plates are in position a mold 38^a is placed around the edges of each hatch and reinforcements are placed in each mold. The projecting reinforcements of the plates are bent up and over such reinforcements 75 and the molds are filled with concrete for forming hatch combings 39. A top dressing 40 of cement or other plastic material is placed over the entire deck surface.

If desired the seams outside of the calking 80 may be pointed up with thin concrete to make the skin of the hull perfectly smooth although this is not necessary.

If it be desired to have ports or other openings in the side plates they may be 85 formed in the same manner as are the hatches.

When the field cast elements have dried and set the wedges 32 are removed and the loop of the wire 31 is severed. The molds 90 are then removed, the projecting ends of the wires 31 are cut off flush with the surfaces from which they project. The wires 37 may be withdrawn from the members in which they rest or the projecting ends of 95 the wires are cut off flush with the surfaces of the members. Certain parts of the cradle may be removed and the vessel launched in the usual manner or it may be launched in the cradle as is common. 100

Before and during the casting and drying of the field molded members the plates are securely held in position from the outside by the cradle and from the inside by a system of troughs which cover every seam 105 and some of which extend from the bottom plates to the level of the deck plates. The seam covering troughs being arranged relatively close together and being braced by the floor beam and deck beam troughs which are braced by the stanchion troughs will be sufficient to support the plates in position during the casting and drying operations; it being understood that additional bracing may be employed if desired. 110

In the building of a house as shown in Figure 9 the same process is carried out with the exception that bottom plates, such as 4 and 9, need not be employed, but such plates may be used in certain structures such as 120 warehouses on piers. In constructing a house by my process the door, window and other openings will be formed as are the hatches and the frames and sills of such may be formed in the same manner as are 125 the hatch combings.

I desire to have it understood that instead of setting up the entire skin surface of the hull before the molding of the field cast members is proceeded with, the plates may 130

be erected in belts and the field cast elements will be molded as new belts are placed in position.

The shop cast elements are few in number as regards size and shape and vessels of any size and tonnage may be constructed by employing a greater or lesser number of plates between the bows and stern.

It will, of course, be understood that all 10 of the molds for the field cast elements may be secured to the reinforcements projecting from the shop cast elements in the same manner that the mold 30 is drawn up to the side plates.

15 In accordance with the provisions of the patent statutes, I have described the principles of my invention, together with the specific method of operation which I consider to best illustrate the same, but I desire 20 to have it understood that such method of operation is merely illustrative, and that the invention may be carried out in other ways.

Having now described my invention what I claim and desire to secure by Letters 25 Patent of the United States is:

1. The herein described process, which consists in setting up shop cast reenforced concrete elements in alinement with their edges in contact, there being a groove in 30 the edges of each plate, the grooves of adjoining plates being in alinement, calking the grooves from the inside forming molds on the inside of the structure and enclosing all of the seams between the elements, 35 introducing concrete into the molds, and then removing the molds.

2. The herein described process, which consists in setting up reenforced shop cast elements in alinement with their edges in 40 contact, there being a groove in each edge of each element, the grooves of adjoining elements being oppositely disposed thereby forming a recess in each joint between elements, the joints being open on one side 45 of the elements thereby permitting access to the recess from the inside, calking the recess and joint from the inside, and molding a reenforced concrete element over the joint.

50 3. The herein described process, which consists in setting up reenforced shop cast elements in alinement with their edges in contact, the edges of the elements being

thickened, the reinforcements projecting at approximately a right angle from the thickened portions, there being a groove in the thickened portions of each element, the grooves of adjoining elements being oppositely disposed thereby forming a recess in each joint between the elements, the joints being open on one side of the elements thereby permitting access to the recess from the inside, calking the recess and joint from the inside, forming a mold enclosing the thickened portions and projecting reinforcements, placing reinforcing members in the molds and supporting said members in position, introducing concrete into the molds, removing the supports, and then removing the molds. 70

4. The herein described process, which consists in setting reenforced concrete elements in alignment, forming a mold on one side of the elements enclosing the joints between the elements whereby the elements 75 become part of the mold, there being reinforcements of the elements projecting into the mold, securing wires to said reinforcements, there being loops formed on said wires extending outside of said mold, forcing wedges into said loops to securely fasten said mold into place, introducing concrete into mold, and then removing the mold. 80

5. The herein described process which consists in setting reenforced concrete elements in alignment, setting up mold plates on one side of the elements to enclose the joints between the elements whereby the elements become part of the mold, there being reinforcements of the elements projecting into the mold, passing both ends of U-shaped wires through one of the mold plates, securing both ends of the wires to the reinforcements of said elements, then forcing wedges between the protruding loops 90 of the U-shaped wires and the mold plates to securely fasten said mold plates into place, introducing concrete into the mold, and then removing the mold. 95

This specification signed and witnessed 100 this 24th day of January, 1918.

JOHN T. SIMPSON.
